ABSTRACT

A device whereby a coat carried on a coat hanger can be checked and secured after insertion of a coin and subsequently redeemed by the use of a removable key. The device includes a movable support member adapted to support the coat hanger in one position, and a plunger secured on the end of a chain which can be passed down the sleeve of a coat and then inserted in the device to simultaneously lock the support member against movement, eject the coin for collection and cause a latch to latch the plunger against withdrawal. The latch can subsequently be released by means of the key.

COIN PRIMED DEVICE FOR CHECKING AND SUPPORTING AN ARTICLE

The invention relates to a coined primed device for checking and supporting an article on a detachable carrier, and in particular to such a device for checking and supporting a coat carried on a coat hanger.

It is among the objects of the present invention to provide a coat checking device whereby a coat can be checked by the owner subsequent to the insertion of a coin and secured against theft or inadvertent removal. The coat can be redeemed by the use of a key which is retained by the owner whilst the coat is checked on the device. The use of the device of the invention provides security for coats in restaurants and similar establishments without the necessity for employing an attendant.

The invention therefore provides a coin primed device for checking and supporting an article on a detachable carrier, comprising means movable between support and release positions for a carrier, means for receiving a coin in a priming position, and a mechanism, operable when a coin is present in the priming position, to latch the supporting means in the support position, discharge the coin for collection and self latch in the operated condition. The device is preferably releasable by the use of a key which can be removed from the device for retention by the owner of the article when checked on the device.

One embodiment of the invention will now be described with reference to the accompanying drawings in which,

FIG. 1 is a front view of an assembly of devices according to the invention for use in checking coats,

FIG. 2 is a front view of a device according to the invention,

FIG. 3 is an elevation on the line 3-3 of FIG. 1,

FIG. 4 is a view on the line 4-4 of FIG. 3,

FIG. 5 is an elevation on the line 5-5 of FIG. 1,

FIG. 6 is a plan view, partially broken away on the line 6-6 of FIG. 2,

FIG. 7 is a rear elevation, partially in section, on the line 7-7 of FIG. 3, and

FIG. 8 is a side elevation similar to FIG. 3, partially in section and showing the device in an operating condition, and

FIGS. 9 and 10 are respectively an elevation and plan view corresponding to FIGS. 5 and 6 of a modified construction.

Referring first to FIG. 1, this shows a box frame structure 1, which may for example be made of sheet metal. The upper portion of the structure is formed as a coin box in which a number of devices 2 according to the invention are secured in side by side arrangement for supporting coat hangers 3. For each device 2, one end of a chain 4 is secured to the coin box, the free end of the chain carrying a plunger 5. In FIG. 1, coat hangers 3, chains 4 and plungers 5 are shown only for the first two devices 2. It will be appreciated that such elements are provided for each device. As each of the devices 2 is identical, the construction of one only will be described below with reference to FIGS. 2 to 8.

Referring first to FIG. 2, the device 2 comprises a face plate 6 having a coin slot 7 in the upper portion and a substantially T-shaped slot 8 at the lower end. The T-shaped slot 8 is adapted to receive therethrough the T-shaped head 9 of a rod 10 extending from coat

hanger 3. The head 9 and rod 10 replace the conventional wire hook normally present on coat hangers. The face plate 6 has secured therein a cylinder lock 11 which can be rotated by means of a removable key 12. A circular aperture 13 is also formed in the face plate to define the forward end of a cylinder 14 (see FIGS. 4, 5, 6 and 8). A piston 15 is movable within the cylinder 14, with the head of the piston normally being substantially flush with the face plate 6.

10 The cylinder 14 projects rearwardly from the face plate 6 and is provided with a latching slot 16. A cranked latching plate 17 has one end mounted for rotation with the cylinder 18 of the cylinder lock 11. The latching plate 17 is biased to rotate in a clockwise direction, as seen in FIG. 7, by a coil spring 42 connected as described below. Above the latching plate 17, the rear surface of the face plate 6 has an integrally moulded stop 6a to prevent excessive movement of the latching plate and overloading of the spring 42. The

20 other end of the latching plate is recessed as shown at 19 in FIG. 4, and movable during rotation of the cylinder lock through the latching slot 16. The plunger 5 (FIG. 2) is provided with a cylindrical portion 20 which can be engaged in the cylinder 14 as far as a shoulder

25 21. The portion 20 is provided with an annular keeper recess 22 which is engageable in the recess 19 in the latching plate 17 in a manner to be described below. The rear end of the cylinder 14 is provided with an inwardly directed flange 23, and a coil spring 24 is positioned in the cylinder between the flange 23 and the end of the piston 15 so as to normally bias the piston forwardly in the cylinder. A spindle 25 projects rearwardly from the piston 15 so that when the piston is depressed against the bias of the spring 24, the spindle 25

30 35 projects through the flange 23 and beyond the rear end of the cylinder. The piston 15 is also provided with a laterally projecting lug 26 as best seen in FIG. 4. The purposes of the spindle 25 and lug 26 will be described below.

40 45 At the rear of the face plate 6, the coin slot 7 opens into a coin chute 27 which extends downwardly, as best shown in FIG. 3, to a coin priming position in which a coin 28 is shown. In this position, the coin 28 is retained between a first coin stop 29 formed integrally with the face plate 6 and a second coin stop 30 which is movable as described below. In the position shown however, the spacing between the coin stops 29 and 30 is slightly less than the diameter of the coin 28 so that the coin is prevented from further downward movement. As best seen in FIG. 3, with the coin 28 in the priming position, the lug 26 projecting from the piston 15 lies on an extended diameter of the coin. A guide slot 27a is formed in the wall of the coin chute 27, so that upon movement of the piston rearwardly in the

50 55 cylinder, the lug 26 will move along the guide slot and bear upon the coin 28 to force it leftwardly as shown in FIG. 3, thus causing corresponding movement of the coin stop 30.

56 Turning now to FIGS. 5 to 8, the coin stop 30 is formed integrally with an arm 31 dependent from a lower outer corner of a triangular plate 32. The plate 32 is pivoted at 33 to the outer side wall of the coin chute 27. A lug 34 projecting laterally from the arm extends past the coin chute and has one end of a coil spring 35 connected thereto, the other end of the coil spring being connected to a lug 36 provided on the outer side of the coin chute. The spring 35 thus normally pivots the plate 32 about the pivot 33 so as to bias

the coin stop 30 inwardly against the coin chute, as shown in FIG. 3. At the inner lower corner of the plate 32 adjacent to the rear of the face plate 6, a latch retainer lug 37 is formed integrally therewith. With the plate 32 in the position shown in FIG. 3, the lug 37 retains the latch plate 17 against the bias of the lock spring and out of engagement with the latching slot 16.

At the rear end of the cylinder 14, a pair of trunnion blocks 38 extend downwardly. A horizontal pivot pin 39 extending between the blocks engages through a lug 40 formed on a lever 41 so as to permit limited relative movement of the lever relative to the face plate 6. One end of the pivot pin 39 projects laterally beneath the coin chute 27 to deflect coins falling from the chute rearwardly into the coin box. At the front end, the lever 41 is provided with a vertical wall member 43 which bears against the lower side of the cylinder 14 to prevent clockwise movement of the lower beyond a horizontal position. The coil spring 42 connects the wall member 43 to the latching plate 17 so as to simultaneously urge the wall 43 upwardly and cause clockwise rotation of the latching plate as seen in FIG. 7. A horizontal wall member 44 is also provided at the forward end of the lever 41 which projects towards but lies slightly clear of the face plate 6. The wall member 44 is recessed at 44a at a mid position coincident with the T-shaped slot 8 in the face plate 6 so as to permit the rod 10 of a coat hanger to be moved therethrough and located with the T-shaped head 9 thereof supported on the wall 44.

To the rear of the lug 40, the lever 41 is formed with a post 45 normally spaced rearwardly from lug 38 to leave a space 45a therebetween, see FIG. 5. When the lever 41 is pivoted in an anticlockwise direction against the bias of spring 42, as shown in FIG. 5, the post 45 enters the space 45a adjacent the trunnion blocks 38, and the wall member 44 moves downwardly and away from the face plate 6, so that a coat hanger supported thereon can be released.

At the rear end of the cylinder 14, an interrupter plate 46 is pivoted at 47. The interrupter plate 46 is balanced so as to normally lie in the position shown in solid lines in FIG. 7. The plate 46 has two wings, and in the position shown the first wing 48 extends between the coin stops 29 and 30 so as to intersect the priming position for the coin in the coin chute 27. The outer edge of the wing 48 is formed as a camming edge which responds to the reception of a coin in the priming position by rotating clockwise as shown in FIG. 7. The other wing 49 of the plate 46 extends around the axis of the cylinder 14 as best seen in FIG. 7. When rotated clockwise as a result of the introduction of a coin into the coin priming position, the wing 48 of the interrupter plate moves between the post 45 of the lever 41 and the trunnion blocks 38 whilst the wing 49 is moved to a position where the end portion thereof lies substantially upon a diameter of the cylinder 14. The purpose of this arrangement will be described below.

The length of the arm 41 and the normal tension in the spring 42 are set in relation to the total weight of the coat hanger 3 such that the arm will support the coat hanger in an unladen condition, but such that when a coat is loaded thereon, the arm will tip as shown in broken lines in FIG. 3 to release the hanger.

In using the device above described, a coin is first introduced through the coin slot 7 into the coin chute 27. The coin falls to the coin priming position 28 where it is retained between the coin stops 29 and 30. As the

coin falls, it cams the interrupter plate 46 so that it assumes the position shown in broken lines in FIG. 7 with the wing 48 in the space 45a interposed between the post 45 and the trunnion blocks 38, as shown in FIG. 5. A coat can now be loaded on the coat hanger 3 and the rod 10 introduced through the T-shaped slot 8 so that the head 9 is located on the wall 44 of the lever 41. The wing 48 of the interrupter plate 46 prevents the post 45 from moving into space 45a so that the lever 41 is retained in a substantially horizontal position and can now support the loaded hanger. Prior to this action, a loaded hanger hung on the member 44 would cause lever 41 to tilt so that the hanger would drop off.

The plunger 5 on the free end of the chain 4 is then passed down the sleeve of the coat and manually inserted through the aperture 13 into the cylinder 14. The piston 15 is consequently urged rearwardly against the bias of spring 24 so that the spindle 25 projects through the rear end of the cylinder. In this position, the spindle 25 lies in the anticlockwise path of rotation of the wing 49 forming part of the interrupter plate 46. The interrupter plate 46 is thus prevented from rotating anticlockwise under gravity while the coin is simultaneously removed from the coin priming position as described below.

The rearward movement of the piston simultaneously causes the lug 26 to bear against the coin 28 and urge it leftwardly as shown in FIG. 3 so that the stop 30 is similarly moved. The triangular plate 32 is consequently rocked rearwardly about the pivot 33 so that the retainer lug 37 disengages from the latch plate 17. The coil spring 42 then biases the latch plate 17 through the latching slot 16 of cylinder 14 so that the recess 19 engages with the annular keeper recess 22 of the plunger 5. The keeper recess 22 is of an axial dimension somewhat greater than the thickness of the latching plate 17, so that upon release of the plunger, the spring 24 urges the piston and plunger slightly forward. In consequence, the spacing between the stop 30 and the lug 26 is increased to an amount greater than the diameter of the coin 28, which thus falls onto the extended pivot pin 39 for deflection into a coin collecting box (not forming part of the invention). The interrupter plate 46 is then retained in the latching position by the weight of the coat and spindle 25 engaging with the wing 49 of the interrupter plate. The key 12 can now be removed from the cylinder lock 11 for retention by the owner of the coat.

When it is desired to redeem the coat, the key is inserted in the lock 11 and rotated to raise the latch plate 17 clear of the cylinder. The spring 24 drives the piston 15 forwardly and ejects the plunger 5, simultaneously withdrawing the spindle 25 into the cylinder. The interrupter plate does not however immediately return to its original position as it is trapped between the post 45 and the trunnion blocks 38 by the weight of the hanger and coat.

The raising of the latching plate 17 simultaneously permits the triangular plate 32 to return to its original position under the influence of spring 35 so that the latching lug 37 again engages beneath and retains the latching plate 17 clear of the latching slot 16. The coin stop 30 is also returned to its original spacing from the coin stop 29. As the rod 10 of the coat hanger is now lifted through the T-shaped slot 8 in the face plate 6, the spring 42 biases the lever 41 in a clockwise direction as shown in FIG. 5, and frees the interrupter plate 46 so that it can return by gravity to its original position

shown in solid lines in FIG. 7. The device is now ready to accept another coat checked thereon as described above.

FIGS. 9 and 10 show a modified construction in which the spring 42 is omitted. In order to provide the biasing force on the lever 41 for supporting the coat hanger, the lever 41 is provided with a rearward extension 50 having an integrally cast counterweight 51 at its end. A clockwise biasing action is at the same time applied to the latching plate 17 by a coil spring 53 engaged around the barrel 18 of the lock, one end of the spring (not shown) being secured to the barrel and the other end being formed as a hook 54 engaged with an edge of the latching member.

We claim:

1. A coin primed device for checking and supporting an article on a detachable carrier comprising:

a frame structure,

a carrier support member mounted for movement in said frame structure between support and release positions for a detachable carrier,

means biasing said carrier support member towards the support position,

a coin receiver defining a priming position for a coin of predetermined diameter,

primary control means responsive to the reception of a coin of predetermined diameter in said priming position to prevent movement of said carrier support member out of said support position, and

second control means for simultaneously moving a coin from the priming position to a release position and for latching said carrier support member in the support position.

2. A coin primed device as claimed in claim 1, wherein said carrier member comprises a lever journaled in said frame.

3. A coin primed device as claimed in claim 2, wherein said biasing means comprises a coil spring connected and tensioned between said lever and another portion of the device.

4. A coin primed device as claimed in claim 2 wherein said lever is journaled at a position intermediate the ends thereof, and wherein said biasing means comprises a counterweight at one end of the lever whereby the other end is biased into a support position for a detachable carrier.

5. A coin primed device as claimed in claim 4, wherein said weight is sufficient in value to support an unladen detachable carrier at said other end of the lever.

6. A coin primed device as claimed in claim 2 wherein said frame structure comprises a face plate towards the rear of which the lever extends in closely adjacent relation when in the support position so as to support a detachable carrier between the lever and the face plate.

7. A coin primed device as claimed in claim 1 wherein said coin receiver comprises a coin chute and stop means associated with said coin chute for receiving a coin of predetermined diameter, said primary control means comprising an interrupter member having a camming edge and mounted for movement in said frame structure between a first position in which the camming edge intersects the priming position and a second position in which movement of the carrier support member from the support position is prevented, said interrupter member being normally biased towards said first position and being movable therefrom to the

second position by engagement of the camming edge by a coin entering the priming position.

8. A coin primed device as claimed in claim 7 wherein said interrupter member comprises a pivoted plate, normally gravitationally biased into said first position.

9. A coin primed device as claimed in claim 7, wherein said frame structure comprises a face plate, through and down the rear face of which said coin

10 chute extends, said device further comprising a cylinder extending through and rearwardly from said face plate adjacent to said coin priming position in said coin chute, a piston movable in said cylinder and having means for latching engagement with said interrupter

15 member, a lug projecting laterally from said piston into the plane of said priming position, means biasing said piston forwardly in said cylinder, and means responsive to the rearward movement of said coin from the priming to the release position for latching the piston in a

20 rearward position in said cylinder, whereby rearward movement of the piston in the cylinder simultaneously latches the interrupter member in the second position, and shifts coin in the priming position to the release position to cause the piston to be latched, the coin then 25 being released for collection.

10. A coin primed device as claimed in claim 9, wherein said piston latching means comprises a latch plate mounted on the rear of said face plate for rotation into the path of movement of said piston, second biasing means connected between the frame structure and

30 latch plate and biasing said latch plate towards latching engagement, a latch retainer member movably mounted in said frame structure, third biasing means connected between said frame structure and said latch

35 retainer member and biasing said latch retainer member to normally retain said latch plate against the bias of said second biasing means out of latching engagement, and means connected to said latch retainer member for retracting said latch retainer member from re-

40 taining engagement with said latch plate in response to the movement of a coin from the priming to the release position.

11. A coin primed device as claimed in claim 10, wherein said latch plate is mounted for rotation on the

45 cylinder of a cylinder lock extending through and secured to the face plate so as to be rotatable by a key engageable with the lock from the front of the face plate.

12. A coin primed device as claimed in claim 9, and further comprising a plunger engageable in said cylinder for urging said piston rearwardly, said plunger being formed with keeper means for engagement by said piston latching means.

13. A coin primed device for checking and supporting a coat on a detachable coat hanger, comprising:

50 a frame structure including a face plate, a support lever mounted for pivotal movement in said

frame structure between support and release positions for a coat hanger, said lever being biased to support a coat hanger when unladen with a coat,

55 a coin chute extending through and down the rear face of said face plate and defining a priming position for a coin of predetermined diameter,

a cylinder extending through and rearwardly from said face plate and having a latching port formed in a wall thereof,

60 a latch plate mounted for rotation with the cylinder of a cylinder lock projecting through said face plate and biased for engagement through said latching

65

port,
a latch retainer member biased to normally retain said latch plate out of engagement through said latching port and responsive to the planar movement of a coin from the priming position to a release position to release said latch plate,⁵

an interrupter plate having a camming edge and mounted for movement on said frame structure between a first position in which the camming edge intersects the priming position and a second position in which the movement of the support member is prevented, the interrupter plate being gravity biased towards said first position and movable to the second position by engagement of the camming edge by a coin entering the priming position,¹⁰

a piston movable in said cylinder and having means projecting rearwardly for latching engagement with the interrupter plate and a lug projecting laterally from said piston into the plane of the priming position,¹⁵

means biasing said piston forwardly in said cylinder, and a plunger engageable in said cylinder and formed with keeper means adapted for engagement by said latch plate,²⁰

whereby, when a coin is inserted in said coin chute and received in the priming position, said interrupter plate is moved to prevent pivotal movement of the support member and thus permit a coat on a coat hanger to be supported thereon, and when said plunger is moved rearwardly to latch the interrupter plate and simultaneously move the coin from the priming position to the release position so as to release the latch plate through the latching port into latching engagement with the keeper means on the plunger.²⁵

14. A coin primed device as claimed in claim 13, wherein said plunger is secured on one end of a chain, the other end of the chain being secured to the frame structure.

15. A coin primed latching device for a plunger adapted to be retained by a complementary latch member, said device comprising
a face plate,⁴⁰

5
a cylinder extending through and rearwardly of said face plate and defining a reception path for said plunger, said cylinder being formed with a latching port,

a latch plate rotatably mounted at the rear of the face plate for engagement through said latch port with a plunger received in the cylinder,

biasing means connected between said device and said latch plate so as to bias the latch plate through said latching port into the reception path, said latch plate being mounted for rotation with the cylinder of a cylinder lock extending through and secured to the face plate so as to be rotatable against the bias of said biasing means by a key engageable from the front of the plate,¹⁵

a latch retainer element mounted in said device for movement in and out of a position in which the latch plate is engaged and retained in a retracted position clear of said path,²⁰

coin receiving means separate from said reception path and adapted to receive a coin of predetermined diameter into a priming position therein,²⁵

means responsive to the introduction of a plunger into the reception path to move the coin from the priming position into a coin release position, and means connected to the latch retainer element and mounted for movement in the device so as to cause the latch retainer element to release the latch member into latching engagement with the plunger in response to the movement of the coin into the coin release position;³⁰

said means responsive to the introduction of a plunger comprising a piston movable in the cylinder with a spring provided for biasing said piston in a direction opposite to the direction of introduction of the plug member and,³⁵

said piston comprising a lug projecting laterally into the plane which a coin in the actuating position assumes, whereby the introduction of a plunger into the cylinder causes the lug to simultaneously move the coin to the coin release position.⁴⁰
